ORIFICE NEBULIZER

Bain L. McKinnon, Seattle, Wash.

Application October 18, 1954, Serial No. 462,906

9 Claims. (Cl. 299—88.5)

This present invention contemplates the provision of an orifice type nebulizer of simple construction which is a device for the production of fine spray or aerosol but further characterized by having integral means for separating from the primary spray the coarse particles produced therein, and discharging only the classified spray of fine aerosol. This invention is of a nebulizer embodying as the above mentioned means of separation an orifice, as outlet from a spray chamber.

If, in such a device, primary spray is produced within a chamber and air is forced into this chamber and to exit through a small orifice, then if such orifice be shielded from direct impingement of the spray, or otherwise be protected from accumulation of liquid, then only those particles of the spray which are small enough to freely circulate within the chamber and do not condense on impact with its walls, will pass through the exit orifice. Practical utilization of this principle demands that two conditions be well satisfied: (1) that the exit orifice be maintained free of liquid accumulation, and (2) that the primary spray be such as to contain a highly usable portion of fine particles.

It should be noted that the requirement that the outlet, when an orifice, be maintained free of liquid accumulation, is at divergence with common practice in which no thought is given to this factor, but the fundamental limitation of liquid bridging to close the port is overcome by simply providing that the outlet be of sufficiently large size so that it will under no condition tend to bridge over.

As means of producing a suitable primary spray, the device contemplates the employment of a plurality of substantially axially aligned orifices, each of which discharges into a restrictive chamber to the end that maximum turbulence can be created which in turn will break up the projected liquid into very tiny particles and finally into an air borne mist within the chamber. The final discharge is out through a relatively small orifice which is at the apex of an inwardly directed cone to the end that larger particles of liquid will be deflected by the conical surface away from the orifice but will be retained within the nozzle assembly for re-atomization when the bulb is squeezed at future times. Means are provided so that the nozzle forms a leakproof arrangement and thus permits the carrying of the filled device in a hand bag or one's pocket, or it may be used in bed, as tucked under the pillow, for instance. To achieve the over-all purposes of this device, a plurality of concentrically disposed units are employed so as to provide liquid storage and to cause the turbulence required and to further provide receiving space for the globules of liquid which have not been broken down into the desired fineness of spray.

Persons suffering from asthma and sinus troubles find it necessary that they have available means for giving them needed relief and such a device therefore must be capable of being conveniently carried on the person,

2

ready to use at all times. In the past, a large number of devices have been provided in an endeavor to practically serve this convenience. Those observed however have been bulky and hard to carry, but most often were provided with screw-on closures and the like, which necessitated considerable loss of time between the instant of need before the device could be put into operation. In the case of asthma sufferers particularly, this was by no means a practical solution of the problem. In my present device, I provide a very compact unit which may be carried fully charged, but without any need for removing any stoppers or caps or covers. In other words it is ready for instant use at any time. Means are provided within the nozzle device so that no matter in what position the device is carried the liquid is contained within an annular chamber and it is impossible for the unit to leak.

The leakproofing of this device is achieved with the small orifices used, and their number, and particularly in the final discharge orifice, which is mounted in the apex of an inwardly extending cone portion so that an annular ring is provided entirely around the final discharge orifice which is sufficient in volume to hold the liquid with which the device is normally charged. It is therefore believed that in this present orifice nebulizer I have provided a solution for many of the perplexing problems and have thus made available for use a device so badly needed when one is an acute sufferer, and which makes relief immediately available when one suffers intensely from any of the respiratory ills.

The principal object of my present invention therefore is to provide a simple and inexpensive nebulizer which can be made in a small size and still not sacrifice any of its desirable aspects.

A further object is to provide a good primary spray device which with the addition of a nebulizer chamber and a small discharge opening becomes a true nebulizer.

A further object of this invention is to provide an orifice nebulizer which needs no stoppers or caps or the like to prevent it from spilling, or which will necessitate the removal of these closure devices, before it is put into use as by a sufferer in immediate need, or by small children who might not understand the workings of a complicated device.

A further object of this present device is to provide a nebulizer that is readily adaptable to several distinct uses so that it may be readily conformed to the discharge of different types of medicaments required for the treatment of various ills.

A further, and very important object of this invention, is to provide a disintegrator jet which will produce a very fine primary spray and one in which the relative sizes of the plurality of orifices may be varied to suit a wide range of applications.

Further objects, advantages and capabilities will be apparent from the description and disclosure in the drawings, or may be comprehended or are inherent in the device.

In the drawings:

Figure 1 is a perspective view illustrating my device in a preferred form;

Figure 2 is a side elevation of the device of Figure 1 with certain parts broken away, and sectioned, to more fully illustrate the construction thereof;

Figure 3 is a vertical sectional view taken on a diameter through the nozzle portion of this nebulizer, the same being shown on an increased scale;

Figure 4 is a cross sectional view taken along the line 4—4 of Figure 3;

Figure 5 is an enlarged perspective view, partly in section, illustrating the relatively small internal cap employed to provide an additional orifice and to separate the

one relatively large turbulent chamber into two such chambers.

Referring more particularly to the disclosure in the drawings, the numeral 10 illustrates the base member of the nebulizer. This is provided with a tapering plug-like portion 12 so that it may be engaged frictionally tight in the mouth of preferably a seamless hand bulb as 14. The seamless type of hand bulb is much more durable than the kind that is made in two or more parts and then joined together. They do have one characteristic, however, and that is, in order to withdraw the forming tools, the neck sizes are considerably larger than the usual seamed bulbs. This factor, however, instead of being detrimental, works to the advantage of this nebulizer in that it is desirable to have considerable diameter to the plug portion 12 for reasons that will be explained in some detail. Formed as part of base 10 is a concentric upwardly extending discharge tube portion 16 which usually is made somewhat tapering forming a jet discharge passageway. At its upper end tube 16 is substantially closed and is provided with the cone portion as 18, at the free end or apex of which, is a small, diverging jet, sharpened discharge orifice 20. It is to be noted that by having the cone portion 18, the orifice 20 is provided with very thin walls. This construction, following the principle of the flow of a fluid through an orifice, discharges a diverging jet, which in coaction with the other, follows out the principles of this present invention. On its periphery, base 10 is provided with an annular lip 22 which provides the annular groove 24. On the inner wall of groove 24 are provided threads as at 26. Similarly threaded as at 28 is the cap portion 30 of the nebulizer. It will be noted in Figure 3 that as cap 30 is screwed down on threads 26, the lower fit portion 32 of the cap comes into a firm arrangement in the annular groove 24, and thus any leakage that might normally occur between threads 26 and 28 is sealed off by the pressure contact, as at 34, which is of course an annular contact arrangement.

Between the inner surface of plug portion 12 and the tubular portion 16 is an annular cavity 36 forming a liquid reservoir and this is made sufficient in its extent so that the delivery orifice member 40 may be engaged in a tight frictional engagement with the tapering outer wall of tube 16. It is further desirable that the downwardly extending wall 42 of member 40 only takes up a portion of the annular cavity 36. This can be substantially in the proportion illustrated in Figure 3 so that a reasonable storage capacity is provided for liquids that may have passed through the first three orifices and not have passed through the final, small, narrow walled orifice 44 in cap member 30. In order that additional storage space may be obtained for these liquids, the upper portion of cavity 36 is enlarged and tapered as is illustrated at 46 in Figure 3. It is to be noted that this chamber capacity must be large enough to contain the entire charge of liquid at the time of filling the same.

In the interior of wall 42 of member 40 is provided a plurality of fluid passageways as 48. It will be noted in Figure 4 that three such passageways are indicated. The upper end of member 40 is conical in form and the inner surface of the same is also of conical form but of less angle so that where the discharge orifice 50 is formed, the walls have converged so that a lip type orifice is provided. This construction is well illustrated in Figure 3.

Disposed on top of, and concentric with tube 16, is an insert orifice member 60. The structure of this member is best illustrated in Figures 3 and 5 in which it will be noted that the outer surface 62 of the member is chamfered out or beveled at 64 so as to form an annular passageway when the insert is contained within member 40. This annular passageway communicates with a plurality of radially disposed grooves 66 so that a path is provided for fluids through a plurality of channels 48 to

the annular communicating passageway formed by bevel 64 and, finally, the fluid can pass through the slots 66 into the interior 68 of the insert orifice member. A discharge orifice is provided at 70, and while the top of the insert as 72 is flat or normal to the axis of the member, the interior end wall as 74 tapers upwardly to orifice 70 so that a thin wall orifice is thus provided.

The final discharge orifice 44 follows the same general plan of providing a thin-walled orifice. To this end it will be noted that the inner surface 80 of shielding cone 82 is so formed as to run out to a minimum thickness where orifice 44 is formed. Attention is particularly directed to the form of the discharge tube 84 which forms a vapor outlet passageway. This is provided with a flaring outwardly tubular portion and the walls are so formed as to extend well into cavity 86 formed by cap 30. This has a desirable function in the forming of the fine discharge mist, but it has a further desirable characteristic in that, even though quite a bit of liquid is contained within the chamber 86, and the device is tipped upside down, the liquid cannot flow out of tube 84 due to the annular storage chamber 85.

Mode of operation

In preparing for employment of this device, it is filled with liquid to a level not exceeding the capacity of either of the annular chamber 36 or 85. In use bulb 14 is squeezed as by finger pressure and normally air is projected out through tube 16. There is a siphon effect as the air passes out through tube 16 and it picks up liquid from the capillary passageways 48 and then the same are discharged in a diverged spray through tube or orifice 70 into the turbulence chamber 90. This is a relatively small chamber and the fluids in emulsion form are passed out through the orifice 70 into a second turbulence chamber 94 and in so doing a further stage of dispersion occurs. This chamber is likewise small and the emulsion is continued with a high liquid to air ratio. The emulsion then is passed out through an orifice 50 as a second stage of dispersion into the large primary chamber 86. Although insert member 60 and delivery orifice member 40 as shown form the preferred construction, broadly they constitute partition means forming first and second small turbulence chambers 90, 94 having third and fourth small, narrow walled orifices 70, 50.

The highest velocity portion of the spray, which is the central portion of the jet, impinges upon the conical surface 82. As will be noted in Figure 3, orifice 44 is very small in comparison with the conical surface, consequently a relatively small portion of the direct jet will pass out through the orifice and the larger globules of liquid which may have passed through the three former jets, as projected from orifice 50, will impinge upon the conical surface 82 and be carried away from the vicinity of orifice 44. Orifice 44 therefore will normally have as its fluid only the very finely divided particles of liquid and the air which is carrying the same. The jet or siphon effect, however, carries with it the mist that has been caused by turbulent action within nebulizer chamber 86 so that the type of discharge out through the discharge tube 84 will be a very finely divided aerosol and the larger globules of liquid will adhere to the inner wall of chambers 86 and will gravitate down to the reservoir chamber 36.

The fineness of the liquid vapor projected by the nebulizer will be a function largely of the diameters of the various orifices when they are made after the showings in this instant case. In the treatment of asthma, for instance, where a very fine vapor is desired, a satisfactory range of sizes is to have orifice 44 of a diameter of .05 inch, orifice 50 of a diameter of .03 inch, the diameter of the disintegrator jet 92, .035 inch, and orifice or tube 20, .02 inch. The physical properties of the liquid being dispensed govern to a degree the atomizing of that liquid, and for different types of liquid, and less urgent require-

ments for finely divided discharge sprays, these openings may be enlarged and will thus pass out a greater amount of liquid. However it follows that the liquid will not be in as finely divided form. There are many uses, however, where this is not detrimental.

When the discharge has been made and the pressure released upon bulb 14, there will be a suck back by the bulb which must of course bring in enough air to displace the volume of the air and liquid dispensed. This suck back tends to clean out any liquid arrested in or about outlet orifice 44. The return of liquid to the liquid storage well 36 is further assisted by providing a flat base as 88 for bulb 14 so the device will normally be stored in a vertical position.

When the bulb 14 has returned to its normal form there will be no tendency for the liquid within the device to of its own volition pass out through the nebulizer. It is desirable however that the diameter of the orifices be not increased beyond the size where the particular liquid to be used will bridge over the openings. This bridging effect makes full use of the surface tension of the liquid and greatly assists in preventing any leakage of the liquid from the device. If the device is going to be stored for any period, or is to be carried where the discharge tube 84 might become contaminated, it may then be desirable to employ some form of stopper in the outlet or discharge tube 84. Such a stopper, however, is not required to prevent the leakage of liquid, it is merely a sanitary aid.

It is believed that it will be clearly apparent from the above description and the disclosure in the drawings that the invention comprehends a novel construction of an orifice nebulizer.

Having thus disclosed the invention, I claim:

1. A nebulizer, comprising: an annular base having a depending tapered hollow plug and a seamless hand bulb with a mouth fitted on said plug; said base having an upstanding discharge tube formed by a return bend from the bottom of the walls of said plug and having upwardly tapered inner and outer walls and defining an annular cavity between the adjacent walls of discharge tube and plug forming a reservoir for fluids, said discharge tube having at its upper end a first sharp-edged, diverging jet discharge orifice, a delivery orifice member formed by an inverted thimble with upwardly tapered inner walls pressed on said discharge tube and with a domed, convexo-concave base spaced above the upper end of the discharge tube and having in its apex a second small narrow-walled orifice, a cap-shaped insert orifice member disposed in said thimble and having an upper base with a third thin-walled orifice and defining below the base of the insert member a first turbulence chamber and providing above the base of the orifice member and below the base of the thimble a second turbulence chamber, liquid passageway means from said reservoir to said first turbulence chamber, said base having at its upper outer edge an upwardly open annular groove with threaded inner walls and an inverted cup-like cover having its lower edge fitted in said groove with its inner surface threadedly engaged with the threads of the groove and with its outer wall pressed against the outer wall of the groove sealing the assembly, said cover defining a large chamber above said thimble and having in its top an inwardly flanged discharge passageway with an inwardly-directed conical inner end terminating in an orifice discharge opening facing said discharge tube.

2. A nebulizer, comprising: an annular base having a depending hollow plug and a hand bulb with a mouth fitted on said plug, said base having an upstanding discharge tube formed by a return bend from the bottom of the walls of said plug and defining an annular cavity between the adjacent walls of discharge tube and plug forming a reservoir for fluids, said discharge tube having at its upper end a first small discharge orifice, a delivery orifice member formed by an inverted thimble

disposed on said discharge tube and with the base of the thimble spaced above the upper end of the discharge tube and having in said base a second small orifice, a cap-shaped insert orifice member disposed in said thimble and having an upper base with a third orifice and defining below the base of the insert member a first turbulence chamber and providing above the base of the insert member and below the base of the thimble a second turbulence chamber, liquid passageway means from said reservoir to said first turbulence chamber, an inverted cup-like cover having its lower edge secured to the upper portion of said base and defining a large chamber above said discharge tube and having in its top an inwardly flanged discharge passageway terminating in an orifice discharge opening.

3. A nebulizer jet assembly, comprising: an annular base having a hollow plug to be attached to a hand bulb, said base having an upstanding discharge tube formed by a return bend from the bottom of the wall of said plug and defining an annular cavity between the adjacent walls of discharge tube and plug forming a reservoir for fluids, said discharge tube having at its upper end a first sharp-edged, diverting jet discharge orifice, a delivery orifice member formed by an inverted thimble fitted on said discharge tube and with a domed, convexo-concave base spaced above the upper end of the discharge tube and having in its apex a second small narrow-walled orifice, a cap-shaped insert orifice member disposed in said thimble and having an upper base with a third thin-walled orifice and defining below the base of the insert member a first turbulence chamber and providing above the base of the insert member and below the base of the thimble a second turbulence chamber, said thimble and discharge tube having formed therebetween an upright liquid passageway leading from said reservoir to said insert member, said insert member having its lower, outer edge recessed forming an annular liquid passageway in communication with said upright passageway and having a plurality of radial passageways from said annular passageway to said first turbulence chamber for supplying liquid thereto.

4. A nebulizer jet assembly, comprising: an annular base having outer walls and an upstanding discharge tube inside of the outer walls forming a reservoir for fluids between the outer walls and discharge tube, said discharge tube having at its upper end a first discharge orifice, a delivery orifice member formed by an inverted thimble disposed on said discharge tube and with the base of the thimble spaced above the upper end of the discharge tube and having a second small orifice, a cap-shaped insert orifice member disposed in said thimble and having an upper base with a third orifice and defining below the base of the insert member a first turbulence chamber and providing above the base of the insert member and below the base of the thimble a second turbulence chamber, and liquid passageway means from said reservoir to said first turbulence chamber.

5. A nebulizer, comprising: a nebulizer body having means at one end portion forming a jet discharge passageway and having means at an opposite end portion forming a vapor outlet passageway and having a hand bulb operatively connected to said jet discharge passageway, said body having formed adjacent said jet discharge passageway a liquid reservoir, said jet discharge passageway having at its inner end a first small, diverging-jet sharpened orifice and said outlet passageway having a second small, narrow walled orifice and partition means in said body forming third and fourth small, narrow walled orifices between the first and second orifices and defining a first small turbulence chamber between said jet discharge passageway and said third orifice and defining a second small turbulence chamber between said third and fourth orifices and providing a primary chamber larger than the capacity of said first and second turbulence chambers between the fourth orifice and said second orifice, and said body having liquid passageway means extending from said

liquid reservoir to said first small turbulence chamber, said orifices being aligned and said body being unobstructed on the line between said orifices.

6. A nebulizer for a liquid, comprising: a nebulizer body having at one end a jet discharge passageway and having at the other end a vapor outlet passageway and having air supply means operatively connected to said jet discharge passageway, said body having formed therein a liquid reservoir, said jet discharge passageway having at its inner end a first small orifice and said outlet passageway having a second small orifice and partitions means in said body forming third and fourth small orifices intermediate the jet discharge and vapor outlet passageways and generally aligned therewith and defining a first small turbulence chamber between said jet discharge passageway and said third orifice and defining a second small turbulence chamber intermediate said third and fourth orifices and providing a primary chamber larger than the capacity of said first and second turbulence chambers intermediate the fourth orifice and said second orifice, said orifices being of a small size bridgeable by said liquid, and said body having liquid passageway means extending from said liquid reservoir to said first small turbulence chamber.

7. A nebulizer for a liquid, comprising: a nebulizer body having a jet discharge opening at one end and a vapor outlet opening at the other end and a hand bulb connected to said jet discharge opening in free communication therewith, said body having partition means forming a small turbulence chamber over said jet discharge opening and forming a large primary chamber in the area of said vapor outlet opening, said partition means having a small intermediate orifice connecting said turbulence

5

and primary chambers, means forming a reservoir in said body and forming a liquid passageway from the reservoir to adjacent said jet discharge opening, means forming a sharpened, diverging-jet orifice for said jet discharge opening, and means forming an inwardly-directed, conical shield for said vapor outlet opening having a small orifice at its apex of a size bridgeable by said liquid.

8. A nebulizer for a liquid, comprising: a housing forming a chamber having a discharge opening and having spaced from said discharge opening jet means, said jet means having a jet discharge passageway and manually operable means to produce a mixed air liquid stream directed from said passageway toward said chamber and including a partition member covering said passageway having an orifice in axial alignment with said passageway through which said stream must pass to reach said chamber, said orifice being of a small size bridgeable by said liquid.

9. The subject matter of claim 8 in which said jet passageway terminates in a restricted orifice whereby said stream must pass a plurality of orifices to reach said chamber.
